COMBINATION CIGARETTE CONTAINER,
LIGHTER, AND ASH TRAY

Raymond P. Wagner, Willimantic, Conn.

Application February 16, 1950, Serial No. 7,971

Term of patent 14 years

(Cl. D85—2)

To all whom it may concern:

Be it known that I, Raymond P. Wagner, a citizen of the United States, residing at Willimantic, in the county of Windham and State of Connecticut, have invented a new, original, and ornamental Design for a Combination Cigarette Container, Lighter, and Ash Tray, of which the following is a specification, reference being had to the accompanying drawing, forming part thereof.

Fig. 1 is a top plan view of a combination cigarette container, lighter, and ash tray showing my new design.

Fig. 2 is a side view thereof.

Fig. 3 is a front view thereof.

Fig. 4 is a rear view thereof.

I claim:

The ornamental design for a combination cigarette container, lighter, and ash tray, substantially as shown.

RAYMOND P. WAGNER.
